US00D762141S

(12) **United States Design Patent**
Zhou

(10) **Patent No.:** **US D762,141 S**
(45) **Date of Patent:** **** Jul. 26, 2016**

(54) **LOW SPEED ELECTRIC VEHICLE**

(71) Applicant: **Jianhui Zhou**, Guangdong Province (CN)

(72) Inventor: **Jianhui Zhou**, Guangdong Province (CN)

(**) Term: **14 Years**

(21) Appl. No.: **29/517,325**

(22) Filed: **Feb. 11, 2015**

(51) **LOC (10) Cl.** **12-02**

(52) **U.S. Cl.**

USPC **D12/16**

(57) **CLAIM**

The ornamental design for a low speed electric vehicle, as shown.

DESCRIPTION

FIG. 1 is a front elevational view of a Low speed electric vehicle showing my new design;

FIG. 2 is a rear elevational view thereof;

FIG. 3 is a left side view thereof;

FIG. 4 is a right side view thereof;

FIG. 5 is an atop plan view thereof;

FIG. 6 is a perspective view thereof; and,

FIG. 7 is another perspective view thereof.

1 Claim, 7 Drawing Sheets
